US0D1062442S

(12) **United States Design Patent** (10) Patent No.: **US D1,062,442 S**
(45) Date of Patent: ** Feb. 18, 2025

(54) **CARABINER**

(71) Applicant: **ZEDEL**, Crolles (FR)

(72) Inventor: **Paul Petzl**, Barraux (FR)

(73) Assignee: **ZEDEL**, Crolles (FR)

(**) Term: **15 Years**

(21) Appl. No.: **29/854,192**

(22) Filed: **Sep. 22, 2022**

(30) **Foreign Application Priority Data**

Mar. 22, 2022 (EM) 008912554-0001

(51) **LOC (15) Cl.** **09-06**
